UNITED STATES PATENT OFFICE.

SYVER LOE, OF MINNEAPOLIS, MINNESOTA.

INDEPENDENT-VOTE MECHANISM FOR VOTING-MACHINES

No. 895,872.

Specification of Letters Patent. Patented Aug. 11, 1908.

Application filed March 28, 1904. Serial No. 200,464.

To all whom it may concern:

Be it known that I, SYVER LOE, citizen of the United States, residing at Minneapolis, in the county of Hennepin and State of Minnesota, have invented certain new and useful Improvements in Independent-Vote Mechanism for Voting-Machines; and I do hereby declare the following to be a full, clear, and exact description of the invention, such as will enable others skilled in the art to which it appertains to make and use the same.

My present invention relates to voting machines, and has for its object to provide an independent voting mechanism, so-called, the function of which is to permit and to control the voting of the names of the various candidates not represented on any ticket.

To the above ends the invention consists of the novel devices and combinations of devices hereinafter described and defined in the claims.

The independent vote mechanism herein disclosed and claimed is, in the drawings, shown as applied to a voting machine the general features of construction of which are the same, or approximately the same as in my prior patent No. 804,962, issued of date November 21st, 1905, filed of even date here-with, and entitled "Voting machine."

The present invention is illustrated in the accompanying drawings, wherein like characters indicate like parts throughout the several views.

Figure 1 is a view in front elevation, with some parts broken away and others removed, showing one side, or approximately one half, of the complete voting machine. Fig. 2 is a vertical section taken from front to rear of the machine approximately on the line $x^2 x^2$ of Fig. 1. Fig. 3 is a horizontal section taken approximately on the line $x^3 x^3$ of Fig. 2. Fig. 4 is a detail view in plan, showing one of the independent vote slides or keys and certain associated parts, some parts being sectioned on the line $x^4 x^4$ of Fig. 2. Fig. 5 is a vertical section taken approximately on the line $x^5 x^5$ of Fig. 4. Fig. 6 is a transverse vertical section taken approximately on the line $x^6 x^6$ of Fig. 4. Fig. 7 is a plan view of the printing or stamping wheel. Fig. 8 is an end elevation of the said wheel shown in Fig. 7; and Fig. 9 is a plan view of one of the independent vote disks or blanks.

The mechanism of the machine is con-

tained within a case or cabinet 1, having an expanded base 2 and detachable front and rear plates 3 and 4, respectively. Inclosed within this case is a skeleton framework, made up, as shown, of a plurality of vertical angle irons 5, vertical bearing strips 6, and horizontal connecting brackets 7. The bearing strips 6 are located at the front of the machine and are attached to vertically disposed ticket-holding strips 8, which strips 8 close the spaces between the strips 6, and are provided with overturned tickets or ballot strips 2. Rigidly secured to the left hand rear portions of the brackets 7, is a vertically disposed angular stop bar 9. Secured within and to the bottom of the base 2, are shaft bearings 10, only one of which is shown (see Fig. 2). Extending transversely of the machine, at the left hand side thereof, as viewed in Figs. 1 and 3, is a countershaft 11, journaled in the bearings 10, which shaft may receive an oscillatory motion by means illustrated in my said prior patent, which means, however, form no part of my present invention. The keys of the machine, as in the machine of my said prior patent, are in the form of slides, arranged in vertical columns, and mounted to move from front to rear of the machine.

In the present illustration, only a part of the complete machine being illustrated, I have shown but two columns of these slides, or keys, one column being assigned to the Republican party, and the other to independent votes. The slides which are assigned to the Republican party are indicated by the character 12, while those assigned to independent votes are indicated by the numeral 13. These slides are mounted in suitable bearings afforded by the vertical frame bars 5 and 6. In a complete machine, other columns of slides corresponding to the slides 12 would, of course, be provided for other political parties which would necessarily be represented at an election. At their forwardly projecting ends, all of the said slides or keys may be provided with finger pieces 14 by means of which they may be readily drawn forward into so-called "set" positions. Furthermore, the slides of each column are provided at their rear ends with wide faced racks 15, shown as formed by cutting parallel slits therein, as best shown in Fig. 3. The slides 12 are provided with

shoulders 16, and the slides 13 are formed with longitudinal slots 17, which, as shown, terminate at their forward extremities in large perforations 18.

For each horizontally aligned row of slides 11-12, there is an extensible lock bar or shaft made up of a plurality of non-rotary sections 19 and rotary coupling shafts 20. The coupling shafts 20, between the abutting ends of the sections 19, are provided with spur pinions 21, and their oppositely projecting ends are reversely threaded and engage right and left threaded seats in the said non-rotary sections 19. The non-rotary sections 19 are angular in cross section, and engage correspondingly formed seats in the flanges of the bars 5, so that they are free to slide therethrough. For the purposes of the present illustration, it should be assumed that the right hand member 19 as shown in Fig. 3, is fixed against endwise as well as rotary movements, although in the actual machine, an absolutely fixed member 19 will be farther toward the right. An adjustable stop 25 plunger 22 extends to the left from, and has screw threaded engagement with, the left hand section 19. This plunger 22 works through a perforation in the stop bar 9, and is provided with a stop collar 23, which co-30 operates with the said stop bar, to limit the distending movement of the distensible lock shaft or bar made up of the sections 19 and 20, and plunger 22.

The pinions 21 mesh one with each of the wide faced racks 15, and are free to slide laterally thereover under expanding and contracting movements of the lock bar.

For offices to which but one candidate may be elected, such, for instance, as Governor, 40 the distensible lock bars described, in themselves, afford the vote limiting devices, and in such instance, the stop collar 23 of the plunger 22 is normally set one step of movement away from the flange of the lock bar 9, 45 so that a forward movement into a "set" position of any one of the slides or keys of the co-operating horizontal line or series will bring the said collar 23 into engagement with the said lock bar, and thus lock in normal position the other slide or slides of the said horizontal row.

For group voting, additional mechanism is provided, such for instance, as illustrated in my said prior patent.

55 The slides 12 co-operate with registers not illustrated in this application, but which may be of the character illustrated in my prior patent, and upon which the said slides operate under return movements from their "set" 60 to their normal positions.

To simultaneously return all of the "set" slides or keys to normal positions, so-called "restoring bars" 24 are provided. There is one of these restoring bars for each vertical 65 column of slides or keys, and each restoring

bar is connected to the frame work of the machine by a pair of parallel links 25. One of the said restoring bars 24 operates upon the shoulders 16 of the slides 12, and the other, works in the slots 17 of the slides 13, 70 and engages with the rear extremities of said slots to force the said slides 14 back to normal position. Normally the restoring bars 24 stand as shown in Figs. 2 and 3, so that the slides 12 and 13 may be freely drawn forward 75 into "set" positions.

Operative movements may be imparted to the restoring bars 24 by an eccentric 25 carried by the shaft 11 and connected to the lower ends of the said bars by chains 26.

The mechanism so far described is identical, or substantially identical, with that disclosed in my said prior patent. It will, however, be understood, that the improved and novel independent vote mechanism herein-after described and broadly claimed, is capable of application to voting machines of various types and designs, and hence is not limited to use in connection with the mechanism above described.

Independent vote mechanism.—In the base 2 of the cabinet, below the aligned perforations 18 of the slides 13, when said slides are in normal position, is a hopper-like receptacle 27, having in its bottom a slide 28 that normally closes a passage 29 in the bottom of the said base 2. The outer end of this slide 28 is turned upward at 30, and is perforated to pass therethrough a staple 31, secured to the side of the base 2. The yoke of a padlock 32, indicated by dotted lines in Fig. 1, is adapted to be passed through the staple 29, to lock the slide 28 in operative position.

A strip 33 extends vertically up one side of the slides 13 and is rigidly secured to the frame brackets 7. Below each slide 13, in vertical line with its perforation 18, when said slide is in normal position, is an inclined chute 34, one end of which is secured to the supporting strip 33 (see Figs. 4, 5 and 6). 105 Mounted in small bearing brackets 35, secured on one of the bearing plates 8, immediately over each slide 13, is a so-called "printing" or "stamping wheel" 36. These wheels carry peripheral type or dies 37, and are provided with sharp edged peripheral ribs or projections 38. The type or die 37 on the several printing or stamping wheels represent different numerals. As illustrated, in the drawings, forty-one slides 13, and 110 forty-one printing or stamping wheels are provided, and the said printing or stamping wheels, from the top of the column downward, are provided with type or dies representing the successive numerals from 1 to 41. 115

The several printing or stamping wheels 36 co-operate with plates 39, shown as afforded by lateral inturned upper end flanges of the brackets 35. The inner surfaces of these plates 39 engage the under surfaces of the 120

slides 13, and the ribs 38 and type or dies 37 of the wheels 36 run quite close to the upper faces of the said platens. The perforations 18 of the slides 13 are shown as formed with 5 front and rear end notches 18^a, which afford clearance for the wheels 36.

Slotted rest brackets 40, secured to the left hand supporting bar or plate 8, directly underlie the outer ends of the slides 13, as 10 best shown in Figs. 4 and 5.

The independent vote ballots or checks are preferably in the form of disks 41, and are advisably constructed of heavy paper or pasteboard. These blank disks 41 are of a 15 size to loosely fit within the perforations or seats 18 of the slides 13.

The slides 13 at one edge, are formed with ratchet teeth 42 mounted in the frame brackets 7, and in the base 2 is a vertically disposed rock shaft 43 which carries a plurality of slightly yielding lock pawls 44, which pawls coöperate one with the ratchet teeth of each slide 13. The lock pawls 44 are, as shown and preferred, formed by slitting a 25 spring blade, which is secured at one edge to the rock shaft 43. On the lower portion of the rock shaft 43 is a short crank arm 45, and on the counter-shaft 11, is an eccentric 46. A connecting rod 47 is provided at one end 30 with an eccentric strap 48 that works on the eccentric 46, and at its other end, is loosely pivoted to the crank 45, as shown, by a screw 49.

In the normal positions of the parts illustrated in the drawings, the eccentric 46, and connections therefrom to the rock shaft 43, hold the free ends of the lock pawls 44 pressed against the edges of the slides 13, so 35 that when any one of the said slides 13 is drawn forward, either completely or partly to a "set" position, the coöperating lock pawl 44 will engage the ratchet teeth 42 of such slide, and prevent the said slide from being forced back into a normal position by 40 the voter.

Operation.—The operation is substantially as follows:—A voter who may wish to vote for independent candidates, that is, for candidates whose names do not appear on any of 45 the tickets of the several political parties represented, is given any number of the blank disks or ballots 41 that he may desire. With the machine constructed as illustrated, if the voter should wish to vote entirely for independent candidates for all of the offices represented, he would require forty-one blank 50 ballots 41, that being the number of votes to which he is entitled. Nevertheless, if he should be given possession of a larger number 55 of blank ballots, he could not use them to any advantage, for reasons which will presently appear. The voter, having pulled forward into "set" positions, slides representing the votes which he wishes to cast, a certain 60 number thereof being independent vote 65

slides, he places a blank ballot 41 into the perforation or seat 18 of each of such "set" independent vote slides. In Fig. 5, the lower slide 13 is shown as drawn into a "set" position, in which position, its perforation 18 70 stands outward of the plate 8 and over the coöperating rest bracket 40, so that the inserted ballot or disk 41 will then rest upon the said bracket. Either while the blank ballot or disk is thus placed within the perforation of seat 18 of the "set" slide, and supported by the bracket 40, or at any time prior thereto, the name of the candidate for the office represented by the "set" slide is written on the said ballot or disk. It is, of 75 course, evident that when an independent vote slide is drawn into a "set" position, it has the same effect upon the vote limiting lock bar 19—20 as when one of the slides 12 in one of the other columns is drawn into 80 "set" position, and hence, when an independent vote slide which is assigned to an office to which but one person may be elected, is drawn into a "set" position, it causes the other horizontally aligned slide or slides 85 which are assigned to the same office, to be locked in normal positions. Otherwise stated, if the voter elects to cast an independent vote for the office of Governor, for instance, he cannot also vote for one of the 90 candidates on a regular ticket for the same office.

After slides have been "set" representing the entire vote, an oscillatory movement is imparted to the counter shaft 11 by some 100 suitable means under control of the attendant of the machine, such means, however, not being shown, since it forms no part of my present invention but is clearly illustrated in my prior patent already identified. The initial movement of the counter-shaft 11, in the direction indicated by the arrow in Fig. 2, causes the connecting rod 47 to move the lock pawls 44 out of engagement with the ratchet teeth 42 of the independent vote slides 13, thus releasing the said slides, so that they may be restored to normal positions, by subsequent rearward and upward movements of the restoring bar 24. The same continued movement of the 110 countershaft 11 causes the eccentrics 25 to draw upon the chains 26, and thereby move upward and rearward the restoring bars 24, as above stated. Under the above noted operative movements of the restoring bar 24, 115 the right hand restoring bar engages with the shoulders 16 of the slides 12, while the left hand restoring bar engages the rear extremities of the slots 17 of the slides 13.

When one of the independent vote slides 125 13 is thus moved back from a "set" position into normal position, the disk or ballot 41 placed within its seat or perforation 18, is forced under the overlying printing wheel 36, and the said, printing wheel is caused to 130

rotate by the engagement of the peripheral ribs or projections 38 with the ballot or disk 41 and to bring its die 37 into action upon the said ballot or disk, said printing wheel is of such diameter as to be given at least one complete revolution as the ballot or disk 41 passes under the same and thereby print or stamp upon the face of the said disk the numeral which represents the number assigned to the particular slide. The stamped or printed ballot or disk 41, as the slide is given its final movement to normal position, is dropped onto an underlying chute 34, and by the latter, is directed into the hopper 27. Were it not for these devices for printing, stamping or otherwise marking the independent vote ballots or disks, it would be possible, by writing the same name for the same office on a number of blank ballots or disks, and running them into the machine by different independent vote slides, to vote several times for a single candidate and thus cheat the machine. This, as is evident, cannot be done with the said printing or stamping devices, because each will print or stamp upon the different ballots a numeral which indicates the particular office to which the co-operating slide is assigned. For instance, in the arrangement illustrated in the drawings, a ballot 41, having written thereon "John Doe", and having stamped thereon the numeral 3, registers a vote for John Doe for Governor, while if the same name should be found written on another ballot or disk marked with the numeral 4, the vote would be registered for Lieutenant Governor. All of the said actuators of the several columns are, of course, simultaneously restored to normal positions. The means described for locking the independent vote slides against return movements, even though but partly drawn out, is very important. Without such provision, it might be possible to draw a slide several times about halfway out, and each time to pass a check or ballot 41 into the machine.

From what has been said it will be understood that the mechanism described is capable of a large range of modification within the scope of my invention as herein set forth and claimed. The means for printing, stamping or otherwise marking the independent vote ballots so as to indicate the office for which they were voted, I consider as broadly new, and desire to claim the same as a pioneer invention in independent vote mechanism for voting machines.

What I claim and desire to secure by Letters Patent of the United States is as follows:

60 1. In an independent vote mechanism for a voting machine, the combination with a key, by the manipulation of which an independent vote ballot may be deposited, of a printing device for printing a character on the independent vote ballot deposited by the

manipulation of said key, substantially as described.

2. In an independent vote mechanism for a voting machine, the combination with a plurality of keys by the manipulation of which independent vote ballots may be deposited, of a printing device for each key, said printing devices having dies differing in character for each key, and adapted to stamp with different characters the independent vote ballots deposited by the manipulation of the different keys, substantially as described.

3. In an independent vote mechanism for voting machines, the combination with a plurality of keys having ballot-receiving seats, which are normally out of reach of the voter but are adapted to be moved within reach of the voter when the said keys are "set," and a plurality of printing devices having compression dies representing different characters and which devices co-operate one with each key and operate on the independent vote ballots as they are delivered into the machine, by movements of the said keys from their "set" to their normal position, substantially as described.

4. In an independent vote mechanism for a voting machine, the combination with a plurality of key slides having independent vote ballot receiving seats, of a corresponding plurality of impression wheels, having impression devices of different character arranged to engage and act upon said ballots, under movements of said slides back from their "set" to their normal positions, substantially as described.

5. In a voting machine, the combination with several columns of key slides and vote limiting lock mechanism co-operating with said slides, one of the said columns of slides being assigned to independent votes, and each slide of said column having recesses for receiving the independent ballots, of a series of impression wheels, one for each independent vote slide, said wheels having dies of different character arranged for action on the independent vote ballots under movements of said independent vote slides from "set" back to normal position, and means for restoring the said slides to normal position, substantially as described.

6. In an independent vote mechanism for voting machines, the combination with a plurality of independent vote slides, by the manipulation of which the independent vote ballots may be deposited, under movements of the "set" slides back to normal positions, of means for stamping with different characters the ballots deposited by the different slides, pawl and ratchet devices normally preventing return movements of said "set" or partly set slides, means for simultaneously throwing pawl and ratchet devices out of action to release said slides, and means for sub-

sequently returning "set" slides to normal positions, substantially as described.

7. In an independent vote mechanism for voting machines, the combination with a plurality of keys having means by the manipulation of which independent vote ballots may be deposited, of means operated by the keys for automatically printing the ballots

which are deposited, substantially as described.

In testimony whereof I affix my signature in presence of two witnesses.

SYVER LOE.

Witnesses:
